UNITED STATES PATENT OFFICE.

S. MINER TILSON, OF ROCKLANE, INDIANA.

CHURN-DASHER.

SPECIFICATION forming part of Letters Patent No. 298,042, dated May 6, 1884.

Application filed September 12, 1883. (No model.)

To all whom it may concern:

Be it known that I, S. MINER TILSON, a citizen of the United States, residing at Rocklane, in the county of Johnson and State of Indiana, have invented a new and useful Churn-Dasher, of which the following is a specification, reference being had to the accompanying drawings.

This invention relates to dashers for churning, 10 washing-machines, and the like; and its object is to provide a dasher possessing superior advantages in point of simplicity, inexpensiveness, durability, ease of operation, and general efficiency.

15 In the drawings, Figure 1 is a side elevation of my improved dasher. Fig. 2 is a longitudinal sectional view of the same. Fig. 3 is a bottom view thereof.

Referring to the drawings, A designates an 20 air cell or chamber forming the bottom or dasher of the device, and comprising the top piece, B, and sides C, preferably flaring, as shown, the bottom of the chamber being open.

25 D is the dasher-staff, which consists of a tube, E, having its bottom end, F, open, and extending down through the top piece, B, to the plane of the bottom edge of the sides C, while its top end, G, is open. This top end is closed by a cap-piece, H, as herein shown, 30 and in said top is provided a valve, I. This valve preferably is formed by a plate, J, having a leather packing-disk, K, and secured in position by a flat spring, L, on the inside of the said top, the packing of the valve serving 35 to normally close the opening M in top G.

The operation and advantages of my invention will be readily understood. On the downward stroke the air contained in the chamber A and in the tubular staff D will be carried down to the bottom of the churn or vessel, 40 as the valve will close against its escape. On the succeeding upward stroke a vacuum is created at the bottom of the churn, and the valve opens by the atmospheric pressure outside and admits air to supply the vacuum. Thus 45 air is forced through the fluid on both the downward and upward movement of the dasher, which in churning causes the oil and wa-

ter to separate without friction to injure the grain of the butter, so that a better product 50 is secured. The staff is secured to the bottom cell or chamber by transverse braces N, arranged above and below the top piece, B, the series above being at right angles to the series below for purposes of greater strength. 55

I am aware that churn-dashers have been heretofore constructed with a bottom cell, and with a tubular staff having its bottom end entering the cell, and provided with a valve at its top end; and also that braces have been 60 heretofore provided at the point of juncture of the tube and cell. I therefore do not broadly claim this construction, my claim being for my own improved construction and arrangement of parts in which the lower end of the 65 tubular staff extends entirely to the bottom plane of the cell, transverse braces being provided above and below the top of the cell, and an auxiliary cap being fitted to the staff and provided with an improved spring-plate 70 carrying a valve-piece, whereby superior strength of construction and convenience and efficiency in operation are secured.

I claim as my invention—

An improved churn-dasher, consisting of a 75 bottom cell or chamber comprising the im-perforate top and side walls, a tubular cylindrical staff having the open top and bottom ends, the latter end extending down through the top of said chamber to the plane of the 80 bottom edge of the side walls thereof, the transverse braces disposed above and below the top wall at the point of juncture of the said top wall and staff, and the top cap-piece fitted to the top end of the tubular staff, and 85 having the flat spring carrying a valve at its free end, substantially as and for the purpose set forth.

In testimony that I claim the foregoing as my own, I have hereto affixed my signature in 90 presence of two witnesses.

S. MINER TILSON.
